UNITED STATES PATENT OFFICE.

MILTON G. DAVIS, OF WEST SOMERVILLE, MASSACHUSETTS, ASSIGNOR, BY MESNE ASSIGNMENTS, TO THE MUNICIPAL SIGNAL COMPANY, OF PORTLAND, MAINE.

SIGNAL-BOX.

SPECIFICATION forming part of Letters Patent No. 451,689, dated May 5, 1891.

Application filed June 18, 1890. Serial No. 355,824. (No model.)

To all whom it may concern:

Be it known that I, MILTON G. DAVIS, of West Somerville, county of Middlesex, State of Massachusetts, have invented an Improvement in Signal-Boxes, of which the following description, in connection with the accompanying drawings, is a specification, like letters and figures on the drawings representing like parts.

10 This invention has for its object to improve the construction of signal-boxes, such as is shown and described in United States Patent No. 375,083, dated December 20, 1887, granted to M. Martin. As shown in said patent, a 15 locking device is provided for the winding-arm of the signal-transmitter, it consisting of a pivoted lever having upon it suitable pins or projections, which co-operate with a pin or projection on the winding-arm to lock said 20 winding-arm in its abnormal position. I have found in practice that these pins are subjected to great wear, and after the box has been in use some length of time they do not properly co-operate, and hence to provide suitable 25 means by which proper adjustment may be given to said pins is one of the objects of this invention, and I have carried it out by arranging one or both pins eccentrically on a movable or rotatable block.

30 I have also found in practice that boxes are oftentimes deranged by the pull-down rods being tampered with, as by being pulled half-way down and then being allowed to return to their normal position, which result 35 can be accomplished by the mechanism shown in the patent aforesaid. To obviate this difficulty I have provided means for preventing the return movement of the pull-down rod unless given a complete movement, said 40 means being thrown out of engagement with the pull-down rod at a certain time, or when the winding-arm has been moved a proper distance to effect the transmission of the signal on its return movement, and held disengaged during the return movement of the 45 said pull-down rod. Herein the pull-down rod, instead of directly engaging the crank-arm that is attached to the winding-shaft of the transmitter, engages the winding-arm having 50 on it a block of insulating material pro-

vided with a pin, said pin engaging the crank-arm.

Figure 1 shows in front elevation a signal-box embodying this invention, the door of the box being removed; Fig. 2, a vertical section 55 of the face-plate of the box, showing the operating parts; Fig. 3, a detail showing in full lines the crank-arm on the winding-shaft of the transmitter, and in dotted lines the winding-arm connected to it; Figs. 4, 5, 6, and 7, 60 details to be referred to.

The signal-box herein shown comprises a shell or case a , a face-plate a' hinged to it, and a door (not shown) also hinged to it at the opposite side. The box contains a multiple- 65 signal transmitter of any usual or suitable construction—such, for instance, as shown and described in patent to J. C. Wilson, No. 320,032, dated June 17, 1885—said transmitter being contained in a box or case a^3 , attached 70 to a supporting-plate arranged on a face-plate or in any other suitable manner. On the winding-shaft a^4 of the multiple-signal transmitter a crank-arm a^5 is secured. The crank-arm a^5 is slotted at its outer end to receive a 75 pin a^6 , attached to a block a^7 of insulating material, secured to the winding-arm b , pivoted at 2. The winding-arm b has on it a pin 3, which co-operates with contact-springs 4 5, constituting a shunt for the multiple-signal 80 transmitter. The winding-arm b is engaged by a pin c^8 on the pull-down rod c , and by said pin is moved into its abnormal position, as shown in Fig. 4, to wind up the motor of the transmitter. The pull-down rod c is slotted, 85 as at c' , to form guide-passages for stationary guide-pins, and said pull-down rod has at its lower end a pull or finger piece c^2 . The pull-down rod c has formed on it at one side suitable teeth c^4 , which are engaged by a pawl c^5 , 90 pivoted at c^6 to the supporting-plate and held in engagement with said toothed portion by means of a spring c^7 . The pawl c^5 has on it a pin c^8 , which lies in the path of movement of the winding-arm b , and when said winding-arm is moved into its abnormal position, as shown in Fig. 4, the said arm will engage the pin c^8 and throw the pawl out of engagement 95 with the ratchet toothed portion. The winding-arm will be held in its abnormal position by 100

means of the locking-device, to be described, until the pull-down rod has been returned to its normal position independently by means of a spring u^2 , and the winding-arm holding the 5 pawl in disengaged position will allow said return movement of the pull-down rod. The pawl prevents return movement of the pull-down rod, except when it has been thrown out of engagement therewith by means of the 10 winding-arm.

The locking device herein shown, which is alternately designed to engage and release the winding-arm and pull-down rod, is substantially the same as shown in the patent to 15 Martin, aforesaid. It consists of a pivotal plate e , (see Figs. 1, 4, and 6,) having on it pins $e^3 e^3$, the latter adapted to co-operate with a pin b^2 on the winding-arm and the former to be acted on by the inclined end portion u 20 of the winding-arm b , and the pull-down rod c has a shoulder c^6 , which is engaged by the upper end of the said pivotal plate. A spring u' is fastened to the plate e , its outer or free end bearing against the frame-work, the purpose of which spring is to continually press 25 the upper end of the plate e against the pull-down rod c . Instead of the fixed pins $e^3 b^2$, as illustrated in the said patent, and which, as before stated, wear materially, I have arranged said pins so that they may be adjusted, and, as shown, said pins are located eccentrically on blocks or screws 1 5 6, which are adapted to be turned in their bearings and be held, preferably, in fixed position by 30 means of clamping-screws 7 8, as best shown in Figs. 6 and 7. It is obvious that for a limited amount of adjustment but one pin need be eccentric.

The supporting-plate for the operating-

parts and the removable dial having a plate 40 of glass in it, as herein shown, form no part of my invention.

I claim—

1. In a signal-box, a signal-transmitter, a winding-arm, and a pull-down rod having 45 teeth, combined with a pawl adapted to engage the said teeth and to be engaged by the winding-arm when the latter is depressed to disengage it from the aforesaid teeth, substantially as described.

2. In a signal-box, a signal-transmitter, a winding-arm, a pull-down rod, and a locking device, and pins on the winding-arm and locking device, which co-operate to lock the winding-arm in its abnormal position, one of 55 which pins is arranged eccentrically on a movable block or stud, substantially as described.

3. In a signal-box, a signal-transmitter and a crank-arm attached to the winding-shaft 60 thereof, combined with a winding-arm, insulated block thereon, and a pin connecting the insulated block with the crank-arm, substantially as described.

4. In a signal-box, a signal-transmitter, a 65 winding-arm having a pin or projection, and a pull-down rod to actuate it, combined with a locking device having an adjustably-held pin or projection to co-operate with the pin or projection on the winding-arm, substantially as described.

In testimony whereof I have signed my name to this specification in the presence of two subscribing witnesses.

MILTON G. DAVIS.
